UNITED STATES PATENT OFFICE

125,028

DESIGN FOR A CAKE SUPPORT

Amedee J. Michel, Chicago, Ill., assignor, by mesne assignments, to The Canal National Bank of Portland, Portland, Maine, a national banking association of the United States of America, as trustee

Application July 22, 1940, Serial No. 93,827

Term of patent 14 years

To all whom it may concern:

Be it known that I, Amedee J. Michel, a citizen of the United States, residing at Chicago, county of Cook, State of Illinois, have invented a new, original, and ornamental Design for a Cake Support, of which the following is a specification, reference being had to the accompanying drawing, forming part thereof.

Fig. 1 is a top perspective view of a cake support, showing my design; and

Fig. 2 is a bottom perspective view thereof.

I claim:

The ornamental design for a cake support, as shown.

AMEDEE J. MICHEL.
